United States Patent

Des. 235,272

Patented June 3, 1975

235,272

GOLF CLUB HEAD

Martin E. Quast, 8013 Washburn Circle,
Bloomington, Minn. 55431

Filed April 19, 1973, Ser. No. 352,621

Term of patent 14 years

Int. Cl. D21—02

U.S. Cl. D34—5 GH

FIG. 1

FIG. 2

FIG. 3

FIG. 4

FIG. 5

FIG. 6

FIG. 7

FIG. 1 is a top view of a golf club head showing my new design.

FIG. 2 is a left side elevational view.

FIG. 3 is a front elevational view.

FIG. 4 is a right side elevational view.

FIG. 5 is a bottom view.

FIG. 6 is a rear elevational view.

FIG. 7 is an elevational view taken along section line 7-7 on FIG. 6 of the drawings.

I claim:

The ornamental design for a golf club head, as shown and described.
